UNITED STATES PATENT OFFICE

CLARENCE B. DINSMORE, OF FLINT, MICHIGAN, ASSIGNOR TO A C SPARK PLUG COMPANY, OF FLINT, MICHIGAN, A COMPANY OF MICHIGAN

ODOMETER

Application filed December 7, 1928. Serial No. 324,405.

This invention relates to measuring instruments and has been designed as an improvement in the odometer element of a combined speedometer and odometer as used on motor vehicles.

An object of the invention is to render more free and smooth the rotation of the figure wheels of the odometer.

Another object is to lessen the friction between adjacent figure wheels of an odometer employing internal transfer mechanism, which lessening of friction tends to lessen and make more nearly uniform the driven load.

Still another object is to positively utilize the slight frictional resistance between adjacent figure wheels to aid in effecting the rotation of any one wheel by the wheel of next lower denomination.

Other objects of the invention such as long life, durability and efficiency will be understood from the following description.

The invention is shown as applied to an odometer wherein the successive wheels are driven the one from the other by star pinions located within the periphery of the wheels, the power transmission being through the instrumentality of internal gears and transverse lugs on the several wheels.

Fig. 1 illustrates a speedometer of the type described, in side elevation with parts broken away and in section. Fig. 2 is a front elevation also partly broken away and in section.

In structures of this kind a fixed shaft has been used for the rotatable support of a series of figure wheels. The wheels have been provided on the under side of their rims with interior teeth at one edge and with transfer lugs on the other edge. Between the figure wheels there have been used transfer pinions carried by transfer pinion carriers. These carriers have been provided with apertures to receive the figure wheel shaft and with means whereby they are held from rotation. Such carriers have been of substantially the same radial dimension as the figure wheels and they have spaced the wheels apart to the extent of their own thickness. To maintain the star pinion or transfer pinion in accurate driving

relation with the transfer lug and the internal gear such pinions have been provided with circumferential grooves engaging in a slot of the pinion carrier. No novelty is herein claimed for the above described transfer mechanism.

With such a construction it will be understood that there is an annular ring on each side of each figure wheel and that these rings bear against the spacing pinion carrier with the result that some friction is developed between the face of the wheel and the carrier whenever the wheel turns. This friction, although slight, is not negligible. When more than a single wheel is being turned it is obviously multiplied and will act substantially like a multiple disc clutch and tend to retard the action of the figure wheels, requiring a greater effort in proportion to the number of wheels to be turned at any one time. There results in consequence a variable resistance caused by this friction and a jerky action of the driving mechanism takes place owing to this variability of the load to be overcome. The condition is more pronounced in the case of a worm drive for the odometer wheels since such a drive develops an end thrust whereby the friction between the figure wheels and the pinion carrier is augmented. This difficulty is of course less with other types of drives and may be reduced to a minimum through the adoption of the ratchet type of drive as illustrated in the drawings.

The present invention not only aims to eliminate as far as possible this disadvantageous friction but even more to utilize the reduced friction which is negligible as far as its influence in retarding the rotation of one wheel relative to another is concerned, to aid each wheel in turning the next as it does through the instrumentality of the star pinion.

In the drawings numeral 1 represents a casting to inclose a frame 2 carrying both the speedometer and the odometer. The speedometer includes a rotating bar magnet 3, a conical field plate 4, and a rotatable conical speed cup 5, this speed cup being, as shown, between the magnet and the field plate. The details of the speedometer form no part of

the measuring instrument and need be no further described.

The odometer includes a driven decimal wheel 9 provided on its hub with an annular flange carrying fixed thereto a ratchet wheel 11. This ratchet wheel is to be driven by a pawl 7 actuated by an eccentric not shown on the end of the so-called second worm shaft. Retarding brake means for steadyng the action of figure wheel 9 is shown at 8. The wheel 9 with the ratchet 11 and the coaxial figure wheels are mounted on shaft 13 which is supported in arms 12 constituting a part of the die cast frame 2.

15 The several wheels are provided with hubs which are in contact but are of such axial dimensions as to space the peripheral portions of the wheels from each other. As shown the wheel 9 has a hub 14 in contact with hub 16 of the adjacent wheel. The hub 14 is shouldered and on the shoulder is freely mounted a star pinion carrier or disc 15. The shoulder of hub 14 is so positioned as to position the carrier or disc 15 axially between the peripheries of the two adjacent figure wheels. The hubs are also of such dimension as to space the peripheries of these wheels from the intermediate disc 15. The disc is furthermore so positioned that the star pinion carried thereby will be in correct operating relation with the transfer lugs of one wheel and the driven teeth of the other. The carrier or disc 15 in addition to being freely mounted on the hub of wheel 9 is held in position and from rotation by a projection 17 entering a frame slot provided for this purpose.

20 By the arrangement described the annular parts of the wheels at their circumferences do not frictionally engage the pinion carrier, the friction being greatly lessened and taking place only between the adjacent hubs 14 and 16.

25 Any existing friction between these hubs, although negligible insofar as it retards the rotation of one wheel relative to the other, does tend to rotate the second wheel in the direction of the rotation of the first wheel. This is of use when the first wheel is actually rotating the second through the instrumentality of the star pinion. A smooth and comparatively effortless action is produced for the rotation of the odometer wheels as a whole, the action through friction between the wheel hubs tending 30 to rotate each successive adjacent figure wheel in unison with the rotation being imparted to it through the star pinion from the adjacent wheel of lower denomination. A construction such as described will produce 35 in addition to its better action a greater efficiency and a more durable instrument and one having longer life.

I claim:

40 1. In a measuring instrument, a plurality 45 of coaxial figure wheels, said figure wheels

having their hubs in contact, internal transfer mechanism for said wheels including a pinion carrier freely mounted on one of said hubs, said carrier being substantially of the same radial dimension as said wheels, means to hold said carrier from rotation, said hubs being dimensioned to space the wheel peripheries from said carrier.

45 2. In a measuring instrument, a plurality 50 of coaxial figure wheels, said figure wheels having their hubs in contact, said hubs being axially dimensioned to space the wheel peripheries from contact with each other, said contacting hubs including a radially reduced portion adjacent the contacting surface, said 55 reduced portion being within the plane of the space between the wheel peripheries, a pinion carrier mounted on said reduced hub portion, means to prevent rotation of said 60 pinion carrier, and a transfer pinion carried by said carrier in operative relation to said figure wheels.

In testimony whereof I affix my signature.
CLARENCE B. DINSMORE.
